UNITED STATES PATENT OFFICE

110,782

DESIGN FOR A TEXTILE FABRIC

Marcel Mey, Paris, France, assignor, by mesne assignments, to Selznick International Pictures, Inc., New York, N. Y., a corporation of Delaware

Application August 23, 1937, Serial No. 71,277

Term of patent 3½ years

To all whom it may concern:

Be it known that I, Marcel Mey, a citizen of the Republic of France, residing at Paris, France, have invented a new, original, and ornamental Design for a Textile Fabric, of which the following is a specification, reference being had to the accompanying drawing, forming a part thereof.

The figure is a plan view of a textile fabric showing my new design.

I claim:

The ornamental design for a textile fabric, as shown.

M. MEY.
